H. A. NEWBURY.

TABLE.

APPLICATION FILED MAY 18, 1917.

Patented Jan. 8, 1918.

FIG. 1.

UNITED STATES PATENT OFFICE.

HERBERT A. NEWBURY, OF WHITE SWAN, WASHINGTON.

TABLE.

1,253,083.

Specification of Letters Patent.

Patented Jan. 8, 1918.

Application filed May 18, 1917. Serial No. 169,534.

To all whom it may concern:

Be it known that I, HERBERT A. NEWBURY, a citizen of the United States, residing at White Swan, in the county of Yakima and 5 State of Washington, have invented certain new and useful Improvements in Tables, of which the following is a specification.

This invention relates to an improved table and the principal object of the invention is to provide a table having an attachment consisting of a leaf and an adjustable support for the leaf so that the leaf may be held at the desired height and to further so mount this leaf that it may be swung to 15 extend over the top of the table if so desired.

Another object of the invention is to so construct the support for the leaf that it may be connected with the table to one side 20 thereof and to further so construct the table that a receptacle will be provided beneath the top of the table.

This invention is illustrated in the accompanying drawings, wherein:—

25 Figure 1 is a perspective view of the improved table,

Fig. 2 is an enlarged fragmentary vertical sectional view through the table and leaf together with the support for the leaf, and

30 Fig. 3 is a fragmentary sectional view taken along the line 3—3 of Fig. 2.

The table is provided with a top 10 and supporting legs 11, a drawer 12 being provided beneath the top 10 and a bin 13 having a partition 14 being positioned between the supporting legs as shown in Fig. 1. The vegetables to be prepared will be placed in the bin 13, the partition 14 being provided so that the different vegetables will be held 35 separated and prevented from mixing.

The leaf 15 is placed to one side of the table as shown in Figs. 1 and 2 and carries a socket 16 which receives the ball or head 17 at the upper end of the vertically extending bar 18. This bar 18 is provided with teeth and constitute a rack bar which extends into the sleeve 19 secured to one of the side walls of the bin 13 as shown at 20.

In order to releasably hold the rack bar 18 in a vertically adjusted position to retain 50 the leaf at the desired height, there has been provided a latching pin 21 which extends through an opening in the sleeve or housing 19 and engages the teeth of the rack bar as shown in Fig. 2 thus holding the rack 55 bar at the desired height and preventing it from moving downwardly in the sleeve until the pin has been drawn outwardly.

Supporting arms 22 extend from the upper end portion of the rack bar and engage 60 the leaf when in the position shown thus supporting the leaf in the extended position and preventing danger of the leaf being broken off from the bearing 16.

When in use, this leaf may be used in the 65 position shown in Fig. 1 or if so desired, the leaf may be turned to extend over the table. The rack bar 18 can be drawn upwardly if it is desired to raise the height of the leaf and when raised will be held in the 70 raised position by the latching pin 21.

I have therefore provided a table having a leaf and supporting means so constructed that the leaf will be very convenient for use and further so constructed that the support 75 may be connected with tables now in use.

I claim:—

1. A table, a sleeve connected with said table and extending vertically, a rack bar 80 slideable in said sleeve and provided with a spherical head at its upper end, means for releasably holding the rack bar in a vertically adjusted position, a leaf, a socket carried by the leaf and receiving the head of the rack bar, and arms extending from the 85 upper portion of the rack bar and engaging the under face of the leaf to support the leaf extended to one side of the table.

2. A table, a sleeve connected with the table and extending vertically, a rack bar 90 slideable in the sleeve for vertical adjustment, a leaf positioned to one side of the table and connected with the upper end of the rack bar for rotary movement thereon from one side of the table to a position above 95 the table, and arms extending from the rack

bar to engage the leaf when positioned to one side of the table and support the leaf.

3. A table, a support connected with the table, a leaf positioned to one side of the table and connected with the upper end of the support for rotary movement thereon from one side of the table to a position above the table, and means extending from the support to engage the leaf when positioned

to one side of the table and support the leaf.

In testimony whereof I affix my signature in presence of two witnesses.

HERBERT A. NEWBURY.

Witnesses:

N. R. SNYDER,
A. E. MILLER.
